MANUALLY OPERATED AIR BRUSH

Anthony J. Palmer and Robert Lee Palmer, Grove City,
Pa., assignors to Palmer Products Co.

Filed Feb. 7, 1964, Ser. No. 78,554

Term of patent 14 years

(Cl. D62—2)

Fig. 1.

Fig. 2.

Fig. 3.

Fig. 4.

Fig. 5.

FIGURE 1 is a front elevational view of the air brush;
FIGURE 2 is a side elevational view of the air brush;
FIGURE 3 is a top plan view of the air brush;
FIGURE 4 is a bottom plan view of the air brush; and
FIGURE 5 is a three-quarter perspective frontal view
of the air brush showing our new design.

The dominant features of the design reside in the
portion shown in full lines.

We claim:

The ornamental design for a manually operated air
brush, as shown and described.
